ABSTRACT

This invention relates to an integrable solid-state circuit for controlling or regulating the effective threshold voltage of an insulated gate field effect transistor (IGFET). The substrate and the gate electrode of the IGFET are bridged by the series arrangement of a diode operating in the reverse direction and an auxiliary IGFET operated in the saturation range.

INTEGRABLE IGFET CIRCUIT

BACKGROUND OF THE INVENTION

This invention relates to an integrable solid-state circuit for controlling or regulating the effective threshold voltage of an insulated gate field effect transistor (IGFET).

The main difficulty in the manufacture of IGFET transistors and switching circuits, resides in realizing the desired value of the threshold voltage with sufficient accuracy and constancy. In particular, it is difficult to obtain low threshold voltages with a good yield. Low threshold voltages are necessary in cases where the switching circuits, for the sake of obtaining small power losses, are to be operated at low operating voltages.

SUMMARY OF THE INVENTION

It is an object of the present invention to realize constant threshold voltages which are extensively independent of the technology. In particular, the problem resides in the fact of realizing constant low threshold voltages and, in one specific type of embodiment, of realizing the threshold voltage zero.

The general idea of invention for solving this problem resides in the fact of enforcing the constancy of the effective threshold voltage by means of an auxiliary circuit integrable in accordance with semiconductor technology, whereas the actual threshold voltage of the individual transistor may vary within relatively wide limits. By means of the auxiliary circuit it shall be possible to adjust the effective threshold voltage by means of an external auxiliary voltage U_H , to a certain value, for example to the value 0 volt. This auxiliary voltage may be derived from the operating voltage U_{DD} with the aid of a voltage divider.

According to a broad aspect of the invention there is provided an improved integrable solid state circuit for adjusting or controlling the effective threshold voltage of an insulated gate field effect control transistor of the enhancement type, wherein the substrate is applied to ground potential and wherein the input signal with reference to said substrate is applied via a coupling capacitor to the gate electrode, wherein the improvement comprises a semiconductor diode bridging the substrate and the gate electrode of said insulated gate field effect transistor, said diode operating in the reversed direction below the breakdown voltage, an auxiliary insulated gate field effect transistor of the enhancement type forming a series arrangement with said semiconductor diode, said auxiliary transistor operated in the saturation range with a reversed current smaller than the reversed current of said diode, and having a drain electrode at a potential greater than that of the gate potential reduced by the amount of the threshold voltage, and having a substrate applied to ground potential and a source of a constantly adjustable voltage coupled between the substrate and the gate electrode of said auxiliary transistor for controlling the effective threshold voltage of said auxiliary transistor.

Accordingly, and with respect to the substrate, a biasing potential is applied to the gate electrode, which is taken off the diode of a voltage divider consisting of a diode and of an enhancement type auxiliary IGFET. This biasing potential is determined by an auxiliary voltage applied to the gate electrode with respect to the substrate, while the voltage applied to the drain elec-

trode of the auxiliary transistor, has no influence upon the biasing potential within certain limits. The reverse current of the auxiliary transistor must be smaller than the reverse current of the diode.

- 5 In the most simple case and in such a type of integrable solid-state circuit according to the invention, the drain electrode of the auxiliary transistor is applied to a battery voltage, while the auxiliary voltage is obtained therefrom with the aid of an ohmic voltage divider.
- 10 In one further embodiment of the integrable solid-state circuit according to the invention there is provided instead of the ohmic voltage divider an integrable voltage-dividing arrangement, consisting of the series arrangement of two insulated gate field effect transistors and a semiconductor diode. In this particular case, the auxiliary voltage is taken off the series arrangement of these two transistors, with the gate electrodes thereof being electrically connected to the respective associated drain electrodes. In this type of voltage divider too, the reverse current of the series arrangement of these two transistors must be smaller than the reverse current of the diode.

15 The above and other objects of the present invention will be more clearly understood from the following detailed description taken in conjunction with the accompanying drawings in which:

BRIEF DESCRIPTION OF THE DRAWINGS

FIG. 1 shows the basic circuit of an integrable solid-state circuit according to the invention;

20 FIG. 2 explains the voltage division between the transistor T_2 and the diode D_1 of FIG. 1;

25 FIG. 3 sectionally and in a top view on to a semiconductor waver, shows an integrated circuit according to the invention;

30 FIG. 4 sectionally shows the sectional views referred to in FIG. 3, and extending vertically in relation to the semiconductor surface,

35 FIG. 5 the inventive further embodiment of an integrable circuit according to the invention including a circuit for producing an effective threshold voltage of 0 volt;

40 FIG. 6 serves to explain the voltage division between the series arrangement T_3 and T_4 on one hand, and D_2 on the other hand;

45 FIG. 7 shows the mutual conductance g_m as a function of the technological threshold voltage U_{T0} as plotted in a normalized representation $y(x)$;

50 FIG. 8 is the graphical representation of the substrate effect ΔU_{T2} at the transistor T_2 as a function of $U_H - U_{T0}$, as calculated from equations (2) and (4) with respect to different substrate dopings;

55 FIG. 9 is the graphical representation of the mutual conductance g_m as a function of the technological threshold voltage U_{T0} as plotted in a normalized representation $y(x)$;

60 FIG. 10 shows the use of an integrable circuit according to the invention in an arrangement employing complementary insulated gate field effect transistors T_{1p} and T_{1n} with an effective threshold voltage of 0 volt;

65 FIG. 11 shows a circuit diagram of a complementary inverter employing complementary insulated gate field effect transistors by using integrable solid-state circuits according to the invention;

70 FIG. 12, in a top view upon a semiconductor waver, shows the integration of the complementary inverter according to FIG. 10;

FIG. 13 is the graphical representation of the admissible surface charge density N_s as a function of the gate capacitance C_{ox} with respect to the dopings of the substrate, the well and the polycrystalline silicon gate as stated in the associated table I; and

FIG. 14 shows graphical representations in which the speed measure $\bar{y}$ as a function of the surface charge concentration N_s is shown with respect to complementary switching circuits with and without a compensating network.

DESCRIPTION OF THE PREFERRED EMBODIMENT

The basic circuit according to the invention is shown in FIG. 1 and consists substantially of the circuit shown within the dashlined box 7 and forming part of the insulated gate field effect transistor T_1 . Preferably, this circuit is integrated with the transistor T_1 or the entire switching circuit in accordance with the known semiconductor technology, and is supplied with both the operating voltage U_{DD} and the auxiliary voltage U_H via an external voltage divider. In cases where an ohmic voltage divider is used, any arbitrary effective threshold voltage can be adjusted within certain limits by means of the auxiliary voltage.

Between the points B and K there is arranged the internal voltage divider consisting of the diode D_1 and the auxiliary transistor T_2 . Owing to $|U_H| < |U_B|$ it will be seen that T_2 is always in the state of saturation, i.e., the current-voltage characteristic is given by:

$$|I_{T2}| = \begin{cases} |I_{T2, sp}| & \text{for } |U_H - U_{G'0}| \leq |U_{T0}| \\ |I_{T2, sp}| + \frac{\beta_2}{2} [U_H - U_{G'0} - \Delta U_{T2}(U_{G'0}) - U_{T0}]^2 & \text{for } U_H - U_{G'0} > |U_{T0}| \end{cases} \quad (1)$$

wherein:

$I_{T2, sp}$ = reverse current of transistor T_2 ,
 β_2 = its mutual conductance parameter,
 U_{T02} = its normal threshold voltage for $U_{G'0} = 0$,
 $U_{G'0}$ = the voltage at G' as appearing during normal condition and
 $\Delta U_{T2}(U_{G'0}) = \Delta U_{T2}(U_{SB2})$ the so-called substrate effect which adds up to the threshold voltage and which is quite generally given by

$$\Delta U_T(U_{SB}) = \frac{1}{C_{ox}} \sqrt{2\epsilon_0 \epsilon_{SB} q N} \cdot (\sqrt{|U_{SB}| + |2\psi_F|} - \sqrt{|2\psi_F|}) \quad (2)$$

U_{SB} indicates the voltage between the source and the substrate (bulk) of the respective transistor. At T_2 it will be seen that $U_{SB} = U_{SB2} = U_{G'0}$.

In FIG. 1 there are shown p-channel-type transistors. In this case all U-quantities are negative. With positive U's the equation (1) also applies to n-channel-type transistors.

The voltage division at T_2 and D_1 is illustrated in FIG. 2 by the current-voltage characteristics $I(U_{G'0})$ of the two branches of the voltage divider. With respect to the diode there is assumed a constant reverse current $I_{D1, sp}$. Under the condition that

$$|I_{D1, sp}| > |I_{T2, sp}| \quad (3)$$

and by equalling $|I_{T2}| = |I_{D1, sp}|$ there is obtained the rest potential at G' from

$$U_{G'0} = U_H - U_{T02} - \Delta U_{T2}(U_{G'0}) - \delta U_2 \quad (4)$$

with

$$\delta U_2 = \sqrt{\frac{2}{\beta_2} (|I_{D1, sp}| - |I_{T2, sp}|)} \quad (4a)$$

When use is made of the equation (2), the equation (4) can be solved algebraically or graphically according to $U_{G'0}$, so that $U_{G'0}$ and U_{T2} will then be obtained in the form:

$$U_{G'0} = U_{G'0}(U_H, U_{T02}, \delta U_2) \quad (4b)$$

$$\Delta U_{T2} = \Delta U_{T2}(U_H, U_{T02}, \delta U_2) \quad (4c)$$

The effective threshold voltage of the transistor T_1 as enlarged by the auxiliary circuit, and when seen from G , i.e. when controlled via C_2 , will thus become:

$$U_{T_{eff}} = [1 + (C_1/C_2)] \cdot [U_{T01} + \Delta U_{T1}(U_{SB1}) - U_{G'0}] \quad (5a)$$

In this

$$C_1 = C_{T1} + C_{D1}$$

is the sum of the gate capacitance $C_{T1} = C_{ox} \cdot W_1 L_1$ and the parasitic capacitance of the diode D_1 .

With the equation (4) the following will become from equation (5a):

$$U_{T_{eff}} = [1 + (C_1/C_2)] \cdot [U_{T01} + U_{T02} + \Delta U_{T1}(U_{SB1}) + \Delta U_{T2}(U_{G'0}) + \delta U_2 - U_H] \quad (5b)$$

$$U_{T_{eff}} = [1 + (C_1/C_2)] \cdot [U_{T01} + U_{T02} + U_{T2}(U_{G'0}) + \delta U_2 - U_H] \quad (5c)$$

The factor $(1 + C_1/C_2)$ in equations (5a, b, c) is due to the voltage division at the series arrangement of the capacitances C_1 and C_2 , in which case C_1 indicates the oxide capacitance of T_1 , and C_2 indicates a coupling capacitance. Normally, C_2 will be chosen substantially greater than C_1 , so that there will result a large "grid transparency" from G .

The transistor T_1 may be driven capacitively into saturation from G via C_2 by means of a voltage pulse (which is negative in the case of p-channel-type transistors). If, in the course of this, the potential at G , changes from 0 to U_G , then there will appear momentarily at G' the potential

$$U_{G'0} = U_{G'0} + U_G (C_2)/(C_1 + C_2), \quad (6a)$$

which, owing to the high resistivity of the internal voltage divider for $|U_{G'0}| > |U_{G'0}|$ (see FIG. 2) only

decreases very slowly by way of discharge across the diode, again in direction towards $U_{G'0}$.

When assuming constant reverse current, $U_{G'}$, after a period of time Δt , will drop from $U_{G'}$ to

$$U_{G'}^{(2)} = U_G^{(1)} - \Delta t_e \frac{|I_{D1,Sp}| - |I_{T2,Sp}|}{C_1 + C_2}. \quad (6b)$$

When permitting, with respect to the switch-on pulse, a maximum decrease by 10 percent, i.e.,

$$\frac{U_G^{(1)} - U_{G'}^{(2)}}{U_G^{(1)} - U_{G'0}} \leq 0,10$$

there will result as the maximum admissible switch-on period

$$\Delta t_e \leq \frac{0,10 = U_G \cdot C_2}{|I_{D1,Sp}| - |I_{T2,Sp}|}. \quad (6c)$$

If now, at G , the potential is again switched from U_G to O , the $U_{G'}$ will first of all assume momentarily the value

$$U_{G'}^{(3)} = U_{G'0} - \Delta t_e \frac{|I_{D1,Sp}| - |I_{T2,Sp}|}{C_1 + C_2} \quad (6d)$$

but then goes very rapidly back almost near $U_{G'0}$, owing to the low resistivity of the transistor characteristic T_2 for $|U_G| < |U_{G'0}|$ (see FIG. 2), in other words, $U_{G'}$ is clamped near the potential $U_{G'0}$ after the switch-off pulses at G . There will become

$$U_{G'}^{(4)} = U_{G'0} - \delta^* U_{G'0} \quad (6e)$$

wherein $\delta^* U_{G'0}$ is dependent upon the duration of the switch-on pulse Δt_e as well as upon the duration of the switch-off pulse Δt_a . Under the condition that

$$\Delta t_s \ll \Delta t_a$$

the deviation $\delta^* U_{G'0}$, also at a random repetition of the pulses, will not exceed the maximum value

$$\delta^* U_{G'0 \max} = \frac{1}{2} \sqrt{\frac{1}{\beta_2} (|I_{D1,Sp}| - |I_{T2,Sp}|)}. \quad (6f)$$

With respect to the rest value (5c), therefore, the effective threshold voltages will increase during pulse operation to:

$$U_{T0,eff}^* = \left(1 + \frac{C_1}{C_2}\right) \cdot [U_{T01} + U_{T02} + \Delta U_{T2}(U_{G'0}) + \delta U_2 + \delta^* U_{G'0} - U_H] \quad (7)$$

order to cause the rest value (5c) to disappear

$$U_{T0,eff} = 0,$$

there must be set on the potentiometer the auxiliary voltage

$$U_{HO} = U_{T01} + U_{T02} + \Delta U_{T2}(U_{G'0}) + \delta U_2. \quad (8a)$$

Therefore, acc. to (4) and as it should be in this particular case, the following potential is applied to G' :

$$U_{G'0} = U_{T01}. \quad (8b)$$

- 15 A top view of an integrated circuit of the type referred to in FIG. 1, is shown in FIG. 3 of the drawings. Various cross-sectional views of this sandwich-gate structure are shown in FIG. 4. As the conductor material for the intermediate gate G' it is above all suitable 20 to use polycrystalline deposited highly-doped silicon. However, it is also possible to use evaporated metals, such as tungsten or molybdenum. The diffused source region 1 of T_2 simultaneously constitutes the pn-diode D_1 to the substrate 2. The gate G can be realized in the 25 usual way by the evaporation of aluminum. Prior thereto, there is still deposited the dielectric 3 for C_2 on G' . In the interest of a high mutual conductance, C_2 is made as large as possible, i.e., appropriately by combining the following measures:
- 30 a. Large surface for C_2 (see additional surface for C_2 over the thick oxide 4 in FIGS. 3 and 4, into which there are etched the windows 5 and 6).
 b. Use of a dielectric 3 having a high dielectric constant E with respect to C_2 (such as silicon nitride).
 c. Causing the dielectric 3 for C_2 to have a very small layer thickness.

In further embodying the invention, the voltage divider is integrated with the semiconductor switching circuit and may be constructed or built up in such a 40 way that the auxiliary voltage U_H automatically assumes the value U_{HO} as stated in equation (8). On account of this, the effective threshold voltage of transistor T_1 will become

$$U_{T0,eff} = 0.$$

A circuit performing this, is shown in FIG. 5 outside the dash-lined box 7. The external voltage divider consists of two insulated gate-field effect control transistors T_3 and T_4 arranged in series with a diode D_2 . The effect of this voltage divider is illustrated in FIG. 6 by the $I(U_{G''})$ characteristics of the two divider sections. Under the condition that the diode reverse current $I_{D2,Sp}$ is greater than the reverse current $I_{T34,Sp}$ as passing through the control transistors T_3 and T_4 , there will result at G'' the voltage

$$U_{H34} = U_{T03} + U_{T04} + \Delta U_{T4}(U_{T03}) + \delta U_{34} \quad (9)$$

$$\delta U_{34} = \sqrt{\frac{2}{\beta_{34}} (|I_{D2,Sp}| - |I_{T34,Sp}|)} \quad (9a)$$

and

$$1/\beta_{34} = (1/\beta_3) + (1/\beta_4). \quad (9b)$$

When comparing the equations (8) and (9) it will become evident that actually

$$U_{H34} = U_{H0} \quad (10)$$

provided that the two conditions

$$U_{T01} + U_{T02} = U_{T03} + U_{T04} \quad (10a)$$

and

$$\delta U_2 = \delta U_{34} \quad (10b)$$

are met.

Normally, the condition (10a) is always met in the case of an integrated structure, because in that case there may be expected the equality of all threshold voltages ($U_{T0,i} = U_{T0}$) on one crystal.

The condition (10b) only involves a relatively small correction. This condition, however, may also be met by way of suitable dimensioning, because the reverse currents and the β 's in (4a) and (9b) are dependent upon geometry. As is well known, the following applies to the β 's:

$\beta_i = \mu C_{ox} W_i / L_i$ (μ = mobility, C_{ox} = gate oxide capacity per surface, W_i = width and L_i = length of the channel of T_i). In the case of an equal reverse-current difference

$|I_{D1,sp}| - |I_{T2,sp}| = |I_{D2,sp}| - |I_{T34,sp}|$,
equal μ and equal C_{ox} , the condition such as (10b) is met, e.g., by the following dimensioning:

$$W_3 = W_4 = 2W_2$$

With the aid of simple means, however, the effective threshold voltage, instead of to zero, may be compensated to a small defined value which is extensively independent of technology.

According to equations (5c) and (9), the effective threshold voltage is given by:

$$U_{T0,eff} = \left(1 + \frac{C_1}{C_2}\right) [U_{T01} + U_{T02} + \Delta U_{T2}(U_{G'0}) + \delta U_2 - U_{T03} - U_{T04} - \Delta U_{T4}(U_{T03}) - \delta U_{34}] \quad (5d)$$

When purposely deviating now from the conditions (10a) or (10b) which, together cause the square bracketed expression to disappear, it is possible to realize small defined threshold voltage values.

One deviation from the condition (10a) can be realized, for example, in an advantageous manner, by using gate electrodes having a different electron work function ϕ_m . In the case of p-channel transistors, the necessary negative threshold voltage will be obtained when making the sum of all work functions of the gate electrodes of transistors T_1 and T_2 smaller than the corresponding sum of T_3 and T_4 :

$$\phi_{m1} + \phi_{m2} < \phi_{m3} + \phi_{m4}$$

In the case of n-channel transistors the necessary positive threshold voltage is obtainable by realization of the following condition:

$$\phi_{m1} + \phi_{m2} > \phi_{m3} + \phi_{m4}$$

It is of particular advantage to make, in both cases,

5 $\phi_{m2} = \phi_{m4}$ and to make only the work functions of the gate electrodes of T_3 and T_4 different, i.e.

$$\phi_{m1} < \phi_{m3} \text{ for p-channel transistors}$$

$$\phi_{m1} > \phi_{m3} \text{ for n-channel transistors}$$

10 The aforementioned special advantage resides in the fact that in this way there will disappear in (5d) the difference of the substrate effects:

$$\Delta U_{T2}(U_{G'0}) - \Delta U_{T4}(U_{T03}) = 0$$

15 When using silicon gate electrodes, the above conditions relating to p-channel as well as to n-channel transistors may be met by doping the gate electrode of T_3 more highly than the one of T_1 ($N_3 > N_1$) if, as customary, the gate electrodes in the case of p-channel transistors are given a p-type doping, and an n-type doping in 20 the case of n-channel transistors.

Accordingly, the following will result in this particular embodiment for the effective threshold voltage:

$$|U_{T0,eff}| = [1 + (C_1/C_2)] \cdot kT/q \cdot 1n(N_3/N_1) \text{ wherein the condition (10b) is assumed to have been met.}$$

25 Consequently, the effective threshold voltage is independent of the substrate doping and of the concentration of surface charges and surface conditions. It is only still dependent upon the capacitances C_1 and C_2 which are technologically easy to control, and upon the dopings N_1 and N_3 of the gate electrodes. However, no high demands are placed on the accuracy of the dopings N_1 and N_3 , as they only logarithmically enter the expression for the threshold voltage.

30 A small threshold voltage deviating from zero, however, can be realized also in that the condition (10b) is replaced by

$$\delta U_{34} < \delta U_2$$

40 This is accomplished e.g. by suitably selecting the transistor geometries, so that the following relation will be applicable:

$$45 (L_{D2,sp} - L_{T34,sp}) \cdot \left(\frac{L_3}{W_3} + \frac{L_4}{W_4} \right) < (I_{D1,sp} - I_{T2,sp}) \frac{L_2}{W_2}$$

50 The maximum mutual conductance of the circuit according to FIG. 5 is now to be compared with the maximum mutual conductance of the simple insulated gate field effect transistor T_1 , respectively for a control voltage U_{Gmax} .

The following applies to the simple transistor (I):

$$55 g_m^{(I)} = \beta_1 (U_{Gmax} - U_{T0}) \quad (11)$$

The following applies to the circuit (II):

$$60 g_m^{(II)} = \beta_1 C_2 / (C_1 + C_2) (U_{Gmax} - U_{T0,eff}) \quad (12)$$

65 $U_{T0,eff}$ may be calculated from equation (5c). When assuming with respect to the normal case equal threshold voltages on the crystal ($U_{T0,i} = U_{T0}$), and when making, in accordance with equation (10b) $\delta U_2 = \delta U_{34}$, the following will apply to U_{H34} according to equation (9) and according to FIG. 6:

$$U_{H34} = \begin{cases} 2U_{T0} + \Delta U_{T4}(U_{T0}) + \delta U_{34} & \text{for } 2U_{T0} \\ & + \Delta U_{T4}(U_{T0}) \leq U_B \\ U_B & \dots \text{for } 2U_{T0} + \Delta U_{T4}(U_{T0}) \geq U_B \end{cases} \quad (13)$$

and the following applies to the effective threshold voltage according to (5c) and (8b):

$$\frac{C_2}{C_1 + C_2} U_{T0,eff} = \begin{cases} 0 & \dots \text{for } 2U_{T0} + \Delta U_{T4}(U_{T0}) \leq U_B \\ 2U_{T0} + \Delta U_{T2}(U_{SB2}) - U_B + \delta U_2 & \text{for } 2U_{T0} \\ & + \Delta U_{T4}(U_{T0}) \geq U_B \end{cases} \quad (14)$$

ΔU_{T2} is to be calculated according to equations (2) and (4) with $U_{SB2} = U_{G'0}$ and $U_H = U_B$. With respect to the mutual conductance there will now be obtained with the aid of (12) and (14) the following relationship

$$\frac{g_m^{(II)}}{\beta_1} = \begin{cases} \frac{C_2}{C_1 + C_2} U_{Gmax} & \dots \text{for } 2U_{T0} + \Delta U_{T4}(U_{T0}) \leq U_B \\ \frac{C_2}{C_1 + C_2} U_{Gmax} + U_B - 2U_{T0} - \Delta U_{T2}(U_{SB2}) - \delta U_2 & \text{for } 2U_{T0} + \Delta U_{T4}(U_{T0}) \geq U_B \end{cases} \quad (15)$$

or, in a non-dimensional notation, with $x = U_{T0}/U_{Gmax}$ and $y = g_m/(\beta_1 U_{Gmax})$:

$$y^{(II)} = \frac{g_m^{(II)}}{\beta_1 U_{Gmax}} = \begin{cases} \frac{C_2}{C_1 + C_2} & \dots \text{for } x \leq \frac{U_B}{2U_{Gmax}} - \frac{\Delta U_{T4}(x)}{2U_{Gmax}} \\ \frac{C_2}{C_1 + C_2} + \frac{U_B}{U_{Gmax}} - 2x - \frac{\Delta U_{T2}(U_{SB2}(x))}{U_{Gmax}} & \text{for } x \geq \frac{U_B}{2U_{Gmax}} - \frac{\Delta U_{T4}(x)}{2U_{Gmax}} \end{cases} \quad (16)$$

and correspondingly, the following will apply to the simple insulated gate field effect transistor:

$$y^{(II)} = g_m^{(II)}/\beta_1 U_{Gmax} = 1 - x. \quad (17)$$

FIG. 7 shows the normalized mutual conductances $Y^{(I)}$ (x) and $Y^{(II)}(x)$ in a graphical representation with respect to the special case where $U_B = U_{Gmax}$.

The following is applicable with respect to the compensating circuit according to FIG. 5:

$$Y^{(II)} = Y_{max}^{(II)} = C_2/C_1 \dots \text{for } x < x^*$$

$$Y^{(II)} = Y_{max}^{(II)} + \frac{U_B}{U_{Gmax}} - 2x - \frac{\Delta U_{T2}(x, U_B)}{U_{Gmax}} \text{ for } x > x^*$$

and in this case $U_B/U_{Gmax} = 1$. The substrate effect ΔU_{T2} has been calculated from equations (2) and (4) with $U_{SB2} = U_{G'0}$, $U_H = 1.5$ volt, $N = 10^{15} \text{ cm}^{-3}$ and $C_{ox} = 35 \text{ nF/cm}^2$. δU_2 has been neglected.

When neglecting the substrate effect, then $Y^{(II)}(x)$ with respect to the various C-conditions, would be

represented by the dashlines. The solid lines show to have taken into consideration the substrate effect. They are calculated with respect to $U_{Gmax} \approx U_{DD} = U_B = 1.5$ volt, $N = 1.10^{15} \text{ cm}^{16.3}$. With respect to other N-values, FIG. 8 shows the substrate effect ΔU_{T2} as a function of $(U_H - U_{T0})$.

The following may be taken from FIG. 7, as well as from equations (16) and (17):

1. that with respect to a certain medium U_{T0} -range 10 the mutual conductance of the circuit is better than that of transistor $Y^{(II)} > Y^{(I)}$ (hatch-lined in FIG. 7 with respect to $C_2/C_1 = 4$),
2. that with respect to $0 \leq U_{T0} \leq 1/2 \cdot [U_B - U_{T4}(U_{T0})]$ the mutual conductance of the circuit is constant, i.e., independent of U_{T0} .

It is possible to extend the range of constant mutual conductance when choosing U_B to be greater than U_{Gmax} , that is, when applying the outer voltage divider to a special source of voltage $U_B > U_{Gmax}$. This source of voltage is in the course of this only loaded statically with reverse current.

A similar diagram as in FIG. 7 (mutual conductance with respect to threshold voltage) is shown in FIG. 9; in this case, however, with $U_B = 2U_{Gmax}$. Now the threshold voltage U_{T0} may increase up to the magnitude of U_{Gmax} before the mutual conductance starts to decrease. Here, as in the general case, the break point (knee) is lying at

$$U_{T0} = (1/2) [U_B - \Delta U_{T4}(U_{T0})]. \quad (18)$$

In cases where the mutual conductance is supposed to remain constant throughout the entire range

$$0 \leq U_{T0} \leq U_{Gmax}$$

it will be necessary to increase U_B to

$$U_B \geq 2U_{Gmax} + \Delta U_{T4}(U_{Gmax})$$

- 40 The following applies to the simple insulated gate field effect transistor:

$$Y^{(I)} = 1 - x.$$

$$Y^{(II)} = Y_{max}^{(II)} = C_2/(C_1 + C_2) \dots \text{for } x < x^*$$

$$Y^{(II)} = Y_{max}^{(II)} + \frac{U_B}{U_{Gmax}} - 2x - \frac{\Delta U_{T2}(x, U_B)}{U_{Gmax}} \text{ for } x > x^*$$

- 50 IN this particular case with $U_B/U_{Gmax} = 2$. The substrate effect ΔU_{T2} has been calculated from (2) and (4) with $U_{SB2} = U_{G'0}$, $U_H = U_B = 3$ V, $N = 10^{15} \text{ cm}^{-3}$ and $C_{ox} = 35 \text{ nF/cm}^2$. δU_2 has been neglected.

Since the described circuit for realizing an externally adjustable effective threshold voltage, or for realizing an effective threshold voltage "zero," can be applied to p-channel as well as to n-channel insulated gate field effect transistors, it may also be used advantageously in connection with complementary switching circuits.

- 60 The described circuit can be advantageously applied especially to complementary switching circuits of the low operating voltage type, because in this case the simultaneous technological realization of the two threshold voltages for the p- and n-type channel with the desired accuracy, is particularly difficult.

According to the conventional complementary technique the n-channel transistors are accommodated in

the p-doping area, i.e., the so-called p-wells, as diffused into the n-substrate, with this technology, for example, being known from "IEEE Journal of Solid-State Circuits" Vol. Sc-5, No. 1 (February 1970) pp. 24 to 29-in particular FIGS. 1, 3, and 8. Since the n-channel transistors are accommodated in the p-wells, have a substantially higher substrate effect, owing to the relatively high doping of the wells, than the p-channel elements (approximately factor 3 to 5), the mutual conductance already starts to decrease in the diagrams of Gis. 7 and 9, at smaller U_{T0} -values.

Therefore, if only one source of voltage is available ($U_B = U_{DD} \approx U_{Gmax}$) as in FIG. 7 then, in the case of n-channel transistors, the range of a constant mutual conductance is smaller than in the case of the p-channel transistors. This disadvantage can be avoided by employing one of the following measures:

1. Use of a technology enabling the realization of slightly doped p-wells (such as by means of local epitaxy or long-time diffusion). These methods, however, are relatively complicated or difficult to reproduce.
2. Use of a separate power supply $|U_{Bn}| > |U_{Bp}|$ ($U_{Bp} = U_{DD}$) for increasing the voltage at the external voltage divider of the n-channel transistors. Realization of this relatively simple measure is shown by the circuit diagram in FIG. 10.

When adding a third source of voltage U_{DD} , and when making $|U_{Bp}| > |U_{DD}|$ and also $|U_{Bn}| > |U_{DD}|$, the range of constant mutual conductivity with respect to both types of transistors and a common p-well for all n-channel transistors may be extended independently of one another. When choosing $|U_{Bp}| > |2U_{T0p} + 66U_{T4p}|$ (U_{TOP}) and $U_{Bn} > 2U_{T0n} + \Delta U_{T4n}$ (U_{T0n}), mutual conductance will remain constant with respect to both types up to $U_{T0} = U_{Gmax}$.

The following applies to the polarity of the sources of voltage:

$$U_{DD} < 0, U_{Bp} < 0 \text{ and } U_{Bn} > 0$$

3. Building-in individual p-wells for the n-channel transistors T_{2n} and T_{4n} , and short-circuiting the respective source-electrode with the associated well. The substrate effects at T_{2n} and T_{4n} are completely avoided by this, and the dashlines in FIG. 7 are applicable. It should be noted in this respect, that now the diode D_{1n} must be accommodated in the well of the transistor T_{1n} by being separated from T_{2n} .

FIG. 11 shows the circuit diagram of a complementary inverter realized in accordance with proposal 3, having the effective threshold voltage "zero" by employing only one supply voltage. For realizing the inverter, S_p is connected to the n-substrate, and S_n is connected to the p-well of T_{1n} , while D_p and D_n are combined at the output A. Whereas the input is applied to G, the p-wells of T_{1n} and T_{3n} are applied to $U_B (< 0)$. $U_{T0,eff} = 0$ applies in this respect up to the value of the technological threshold voltage of the p-channel transistor T_{1p} as given in equation (18):

$$U_{TOP, max} = (1/2) [U_B - \Delta U_{T4p} (U_{TOP})]$$

The geometrical arrangement including the separate p-wells T_{2n} and T_{4n} is shown in FIG. 12. The diode D_{2n} is most suitably accommodated in the n-substrate, whereas the diode D_{2p} is accommodated in the well of transistor T_{1n} . In this way no additional diffusion operations are required during manufacture. The dashlines 8,

9 and 10 surround p-type conductivity wells, as inserted into the n-type conductivity substrate. The input is applied to E.

It is still possible to go one step further and to apply measure 3 in a corresponding way also to the p-channel transistors of the complementary switching circuit, for the purpose of excluding also in this circuit the substrate effect. Accordingly, with the aid of one source of voltage $U_B = U_{DD} \approx U_{Gmax}$ it is possible to extend the range of constant mutual conductance from $U_{T0} = 0$ to $U_{T0} = U_B/2$.

For the realization there are used the methods of n-epitaxy on a p-substrate with p_+ -insulation diffusion for the n-wells to be insulated of the transistors T_{2p} and T_{4p} , which have proved suitable in the manufacture of bipolar integrated circuits.

FIG. 13 shows the extreme values of the surface charge density N_I (index I for interface) as a function of the oxide capacitance C_{ox} within which N_I is permitted to vary without thus causing the amount of the technological threshold voltage $|U_{T0}|$ to exceed a predetermined maximum value or, in order to exclude depletion types, causing U_{T0} to change the sign.

To U_{T0} there is applicable the formula

$$U_{T0} = \phi_{ms} - (Q_I/C_{ox}) - (Q_B/C_{ox}) + 2\psi_F$$

Wherein

$$\phi_{ms} = \begin{cases} \phi_{G'} - \phi_{substrate} & \text{for p-channel} \\ \phi_{G'} - \phi_{well} & \text{for n-channel} \end{cases}$$

the difference of the electron work functions,

$$\psi_F = \pm (kT/q) \ln (N/n_i)$$

the gap or space between Fermi level and middle of band (positive for p-well, negative for n-substrate),

$$Q_B = \mp 2 \sqrt{| \psi_F | \epsilon O \epsilon Si qN}$$

for the fixed space charge beyond the channel (positive for n-substrate, negative for p-well),

$$Q_I = q N_I$$

surface charges per area under the gate oxide.

The boundary lines N_I (C_{ox}) in FIG. 13 have been calculated for the following dopings:

substrate	$N_{n-substrate} = 10^{15} \text{ cm}^{-3}$	donors
wells	$N_{p-well} = 10^{16} \text{ cm}^{-3}$	acceptors
gate G_n (n-channel)	$N_{G_n} = 1.5 \times 10^{16} \text{ cm}^{-3}$	donors
gate G_p (p-channel)	$N_{G_p} = 1.5 \times 10^{16} \text{ cm}^{-3}$	acceptors

In FIG. 13 there is stated that the admissible surface charge density N_I as a function of the gate capacitance C_{ox} with respect to the dopings of substrate, well and gate as stated in the following table:

TABLE 1

60	Si-zones				
	N, cm^{-3}	ψ_F, V	ϕ_{ms}, V	$\frac{1}{q} Q_B, \text{cm}^{-2}$	
p-Channel	$n\text{-Substrate} \dots 1 \times 10^{15}$	$-0, 2775$			$+0.8 \times 10^{11}$
	pt-gate, poly-Si.	1.5×10^{19}	$+0, 5175$	$+0, 7950$	
n-Channel	p-Well	1×10^{16}	$+0, 3350$		$-3, 10 \times 10^{11}$
	n ⁺ -gate, poly-Si.	1.5×10^{19}	$-0, 5175$	$-0, 8525$	

with

$$qN_i = Q_i = -Q_B + C_{ox}(\phi_{ms} + 2\psi_F - U_{T0})$$

The following applies to the widely hatched area in FIG. 13:

$$O \leq |U_{T0}| \leq 1,50 \text{ V.}$$

This means to imply that within this area there is obtained a constant mutual conductance at an operating voltage $U_B = 2U_{T0} = 3,0 \text{ V}$, if, as has been just described, T_{2n} and T_{4n} as well as T_{2p} and T_{4p} are provided with individual wells. From FIG. 13 it may be taken that $N_i = Q_i/q$ may vary between $-0,3 \times 10^{11} \text{ cm}^{-2}$ and $+2,9 \times 10^{11} \text{ cm}^{-2}$ in cases where the oxide capacitance amounts to $C_{ox} = 35 \text{ nF/cm}^2$. This value corresponds to an oxide thickness of 1,000 angstroms.

The following applies to the closely hatched area in FIG. 13:

$$O \leq |U_{T0}| \leq 0,75 \text{ V.}$$

This means to imply that within this area there is obtained a constant mutual conductance at an operating voltage of $U_B = 2U_{T0} = 1,5 \text{ V}$. In order to be able to fully utilize the maximum variation width extending from about $N_i = +0,05 \times 10^{11} \text{ cm}^{-2}$ to $N_i = +2,77 \times 10^{11} \text{ cm}^{-2}$, it is necessary to enlarge C_{ox} to 59 nF/cm^2 . This can be realized by employing an oxide thickness of 600 angstroms.

With respect to this case, the threshold voltages U_{T0} and U_{Tn} have been plotted against N_i in FIG. 14 (top diagram). Below and above the range

$$0,05 \times 10^{11} \text{ cm}^{-2} \approx O \leq N_i \leq 2,8 \times 10^{11} \text{ cm}^{-2}$$

it will be seen that the p-channel or the n-channel transistors respectively, change to become of the depletion type. In the diagrams shown in the second row of FIG. 14 the normalized mutual conductances Y_p and Y_n , and in the third row the medium normalized mutual conductance

$$\bar{Y} = (y_p y_n) / (Y_p + Y_n)$$

have been plotted against N_i as the measure of the switching speed of a complementary pair of inverters. The curves relating to the simple complementary inverter pair are indicated by the dashlines in FIG. 14 while those relating to the complementary inverter pair including a compensating circuit according to the invention are indicated by the solid lines. The delay time of the inverter pair is inversely proportional to $\bar{Y}$ ($\tau \sim 1/\bar{Y}$).

All of the diagrams shown in the second and third row apply to $U_B = 1,5 \text{ V}$ provided that the substrate effects of T_{2n} and T_{2p} are eliminated with respect to these transistors (as described hereinbefore) by means of separate wells. With respect to the compensating circuit there will then be obtained constant $\bar{Y}$ - values throughout the entire N_i -range (0 to $2,8 \times 10^{11} \text{ cm}^{-2}$). Relative thereto there are assumed equal mutual conductances ($Y_n = Y_p$) for both the n- and p-channel, this being accomplished by suitably selecting the W/L relationships, so that there is compensated for the mobility difference:

$$\mu_p (W/L) P = \mu_n (W/L) n$$

In cases where it is desirable to obtain the constant $\bar{Y}$ -values, i.e., the compensating effect of the circuit, also without the use of separate wells or islands for T_{2n}

and T_{2p} respectively, the voltage U_B must be increased by the substrate effect

$$\Delta U_{T4n} (U_{T0max}) = \Delta U_{T2n} (U_{T0max})$$

5 From $U_B = 2U_{T0max}$
to $U_B = 2U_{T0max} + U_{T4n}$
(that is why it says in FIG. 14: $U_B \geq 1,5 \text{ V}$).

The diagrams shown in the left-hand vertical column of FIG. 14 apply to $U_{DD} = U_B = 1,5 \text{ V}$. It will be recognized that in this particular case the compensating circuit only supersedes the simple inverter as regards the velocity Y , after the capacitance relationship C_2/C_1 exceeds the value 3:

$$C_2/C_1 > 3$$

Of course, in this particular case ($U_{DD} = U_B$) the advantage of the compensating circuit is not of any particular value not even for greater relationships C_2/C_1 .

Towards smaller U_{DD} -values ($U_{DD} < U_B$) the comparison becomes more and more favorable. The diagrams shown in the second and the third column of FIG. 14 (center and right-hand) apply to the cases where $U_{DD} = 0,75 \text{ V}$ or $0,60 \text{ V}$ respectively.

25 In the case of $U_{DD} = 0,75 \text{ V}$, the compensating circuit already for $C_2/C_1 = 1$ is no longer being exceeded by the simple inverter also in the center of the N_i -area. The velocity measure $\bar{Y}$ with respect to the simple inverter and when approaching the boundaries of the N_i -area drops parabolically to zero, while the compensating circuit maintains its constant value, with the amount thereof being determined by:

$$\bar{Y} = C_2[2(C_1 + C_2)]$$

With respect to $U_{DD} = 0,6 \text{ V}$ the simple inverter itself 35 and with respect to $C_2/Chd I = 1$ only reaches in the center of the N_i - area a value of about 75 percent of the constant value of the compensating circuit. In the case of $N_i \leq 0,56 \times 10^{11} \text{ cm}^{-2}$ and $N_i \geq 2,24 \times 10^{11} \text{ cm}^{-2}$ it will be noticed that the Y of the simple inverter 40 will drop to zero.

Accordingly, FIG. 14 shows that the advantage of the compensating circuit resides above all in very low supply voltages U_{DD} when employing an additional source of voltage U_B (which is only loaded by reverse currents). The magnitude of U_B must amount at least to double the maximum appearing threshold voltage U_{T0} . It is remarkable that the circuit may then even be operated by a supply voltage U_{DD} which is lower than the threshold voltage U_{T0} .

55 It is to be understood that the foregoing description of specific examples of this invention is made by way of example only and is not to be considered as a limitation on its scope.

We claim:

1. An improved integrable solid state circuit for adjusting or controlling the effective threshold voltage of a first insulated gate field effect control transistor of the enhancement type, wherein the substrate is applied to ground potential and wherein the input signal with reference to said substrate is applied via a coupling capacitor to the gate electrode, wherein the improvement comprises:

a semiconductor diode bridging the substrate and the gate electrode of said insulated gate field effect transistor, said diode operating in the reverse direction below the breakdown voltage;
an auxiliary second insulated gate field effect transis-

tor of the enhancement type forming a series arrangement with said semiconductor diode, said auxiliary transistor operated in the saturation range with a reverse current smaller than the reverse current of said diode, and having a drain electrode at a potential greater than that of the gate potential reduced by the amount of the threshold voltage, and having a substrate applied to ground potential; and

a source of a constantly adjustable voltage coupled between the substrate and the gate electrode of said auxiliary second transistor for controlling the effective threshold voltage of said auxiliary transistor.

2. An improved integrable solid state circuit according to claim 1 wherein the threshold voltage of said auxiliary second transistor is controlled by a voltage developed across an ohmic voltage divider having one external connection applied to the drain electrode of said auxiliary second transistor.

3. An improved integrable solid state circuit according to claim 1 further comprising:

third and fourth insulated gate field effect transistors; a second diode forming a series arrangement consisting of said second diode and said third and fourth insulated gate field effect transistors, said diode having a reverse current which is greater than that of said series arrangement, said third and fourth insulated gate field effect transistors having substrates coupled to ground potential, having gate electrodes connected to the drain electrode of said insulated gate field effect control transistor, the source electrode of said third insulated gate field effect transistor coupled to ground potential and the gate and drain electrode of said third insulated field effect transistor coupled to the source electrode of said fourth insulated gate field effect transistor, and the gate and drain electrode of said fourth insulated gate field effect transistor connected to said second diode.

4. An improved integrable circuit according to claim 3 wherein the channel lengths L , channel width W and reverse currents $I_{T2,sp}$ of said auxiliary second transistor, the reverse current $I_{T34,sp}$ of the series connection of said third and fourth transistors, as well as the reverse currents $I_{D,sp}$ of said first and second diodes are related by the formula

$$(I_{D2,sp} - I_{T34,sp}) \cdot \left(\frac{L_3}{W_3} + \frac{L_4}{W_4} \right) = (I_{D1,sp} - I_{T2,sp}) \cdot \frac{L_2}{W_2}$$

5. An improved integrable circuit according to claim 4 wherein

$$(I_{D2,sp} - I_{T34,sp}) \cdot \left(\frac{L_3}{W_3} + \frac{L_4}{W_4} \right) < (I_{D1,sp} - I_{T2,sp}) \cdot \frac{L_2}{W_2}$$

10

6. An improved integrable circuit according to claim 3 wherein the gate electrode of said first transistor, in the case of a circuit consisting of N channel transistors, is made from a material having a smaller electron work function and, in the case of a circuit of P channel transistors, from a material having a greater electron work function than the gate electrodes of said first transistor, said auxiliary second transistor and said fourth transistor.

20

7. An improved integrable circuit according to claim 6 wherein all gate electrodes are made of silicon and wherein said gate electrodes are doped with the same conductivity type as the associated source and drain zones, and that said gate electrode of said first transistor in the case of circuits employing P channel transistors, as well as in the case of circuits employing N channel transistors, is more strongly doped than the gate electrodes of the remaining transistors of the same channel type.

30

8. An improved integrable circuit according to claim 7 wherein the source zone of the auxiliary second transistor and the zone of the same conductivity type of said first diode are arranged at the surface of a common semiconductor body.

35

9. An integrable circuit according to claim 8 wherein the source zone of said auxiliary second transistor is combined with the zone of the same conductivity type of said first diode to form one zone.

40

10. An improved integrable circuit according to claim 8 wherein the source zone of said auxiliary transistor is contacted with a layer designed partly as the gate electrode of said controlled first transistor and partly as the electrode of a coupling capacitor arranged prior to the gate electrode of said controlled transistor.
